FRONT WHEEL FENDER FOR TRICYCLE

Frederick E. Purdy, Olney, Ill., assignor to American Machine & Foundry Company, a corporation of New Jersey

Filed Feb. 20, 1969, Ser. No. 15,851

Term of patent 14 years

Int. Cl. D12—14

U.S. Cl. D90—5

FIG. 2

FIG. 1

FIG. 1 is a perspective view of a front wheel fender for tricycle having my design; and

FIG. 2 is another perspective view of the fender.

The side not shown is a mirror image of that shown in FIGS. 1 and 2.

I claim:

The ornamental design for a front wheel fender for tricycle, substantially as shown and described.
